UNITED STATES PATENT OFFICE.

THEODORE SCHERF, OF ENGLEWOOD, NEW JERSEY.

APPARATUS FOR SOFTENING PAPER.

No. 860,696.

Specification of Letters Patent.

Patented July 23, 1907.

Application filed June 19, 1906. Serial No. 322,481.

To all whom it may concern:

Be it known that I, THEODORE SCHERF, a citizen of the United States, residing at Englewood, in the county of Bergen and State of New Jersey, have invented a 5 certain new and useful Improvement in Apparatus for Softening Paper, of which the following is a specification, reference being had to the drawings accompanying and forming part of the same.

In numerous uses to which paper is put it is desirable 10 that the paper be as pliable or soft as possible, consistent with the strength necessary for the given purpose. For example, a paper bag should be made of paper possessing a considerable degree of pliability or softness. A bag made of such paper conforms more closely 15 to its contents, thereby distributing the weight or pressure of the contents more evenly, and its mouth is more easily gathered or folded by the hand and can be more securely closed, as is particularly desirable where the contents of the bag are of a powdered or granular character. Paper to be wrapped around electrical conductors or other parts of electrical apparatus for the purpose of insulating the same should also be soft and pliable. Such paper conforms more closely to the 20 contour of the object to be covered, and the work of wrapping or covering can be done more easily and rapidly. Paper for the manufacture of artificial or imitation leather should also be of the same soft and pliable character to produce the most effective imitation of the natural article, both for the desired flexibility and to permit the production of embossed patterns without cracking or tearing under the pressure of the embossing dies. Numerous other uses might be 25 mentioned where paper of the character described is desirable, but those mentioned are sufficient to show its wide and diversified field of utility. Practically all the papers now made, however, which possess the tensile strength necessary for their manifold uses, possess also an undesirable degree of stiffness, which does not permit them to bend readily and frequently causes 30 them to form hard creases or folds when bent on an arc of short radius, or to become creased or wrinkled in handling. This lack of pliability is a serious drawback for many purposes for which the paper is used, as already pointed out, and efforts have therefore been 35 made to provide means for eradicating this objectionable stiffness and imparting to the paper the much desired softness and pliability. So far as I am aware, however, none of the previous efforts in this direction has been wholly successful in practice.

40 I have therefore been led to devise my present invention, which has for its chief object to provide an apparatus or machine for treating paper and giving it practically any desired degree of softness and pliability.

45 A further object is to provide a machine, for the pur-

pose mentioned, which shall be simple in construction and rapid and efficient in operation.

In carrying out the invention in the preferred form I provide one or more crimping mechanisms, each consisting, preferably, of a pair of corrugated or bladed 50 rolls, intermeshing to a greater or less depth. The rolls are rotated at suitable speed, and the paper is passed between the same, so as to be subjected to their crimping or corrugating action, with the result that the paper is bent sharply back and forth at more 55 or less closely adjacent points over its entire extent. The natural effect of such treatment would be to produce alternate ribs and grooves, but this effect is prevented by causing the paper to pass through the rolls at a rate of speed somewhat greater than the peripheral 60 speed of the rolls, as by winding it on a drum or roller which rotates faster than the said crimping or breaking rolls. Consequently there is a positive slip or drag of the paper over the breaking or crimping blades, so that the successive bends produced by the intermeshing 65 blades are smoothed out as fast as they are formed, leaving the paper perfectly smooth, but in a soft and pliable condition.

A simple machine of this character is illustrated in the annexed drawings, in which

80

Figure 1 is a sectional side elevation of the machine. Fig. 2 is a detail view showing the action of the crimping or breaking rolls. Figs. 3 and 4 are transverse sectional views on lines III.—III., and IV.—IV., respectively. Fig. 5 is a detail view of one of the spreaders interposed between the sets of breaking rolls to prevent 85 wrinkling of the paper.

The breaking or crimping rolls A, journaled in side frames B, B', are provided with radial breaking, crimping, or kneading blades a, and are arranged in 90 pairs, as shown. The first pair or set, at the left of the machine as viewed in Fig. 1, intermesh to a slight depth, while the other sets intermesh to successively greater depths. Extending longitudinally of the machine, and mounted on bearings carried by arms b projecting 95 from the side frame B', is a driving shaft C, provided at points immediately below the roll-sets with driving worms or screws c, and at one end with a driving pulley c'. The worms or screws c mesh with worm gears c² on the lower breaking rolls, while on the same shafts 100 as the latter are gears c³ which mesh with similar gears c⁴ on the shafts of the upper rolls. The driving mechanisms just described are preferably of the same size and proportions, so that all the rolls will be rotated at the same speed. It is also desirable that the teeth on 105 the roll-driving gears be in register with the blades on the rolls, as clearly shown in Fig. 1, so that the proper lateral spacing of the blades on one roll relative to those on the other will be positively maintained.

At the left of the machine are standards or supports, 110

one of which is shown in Fig. 1 at D, in which is journaled a shaft or mandrel *d* for carrying the roll of paper *E* which is to be softened. At the other end of the machine is a winding drum *F*, mounted on similar standards or supports *f* and provided with a driving pulley *f'* at one end thereof.

The driving shaft *C* being rotated, preferably by means of the mechanism hereafter described, the web of paper *E* is introduced between the first set of breaking or kneading rolls, and is carried thereby to the next set, and so on through the succeeding sets. Issuing from the last set the paper is carried to the winding drum *F*, on which it is wound.

The action of the breaking or kneading rolls is illustrated in Fig. 2, in which it will be seen that the effect of the blades is to bend the paper more or less sharply over the co-operating blades, first in one direction and then in the other. The natural result of such action would be to leave the paper in a corrugated or crimped condition, but such a result is prevented, as previously stated, by drawing the paper through the rolls at a higher rate of speed than that at which it would travel if carried forward only by the rolls themselves. Hence the paper is not only bent over the blades in succession, but is also drawn firmly over their edges. This slip of the paper relative to the blades causes the line of fold over the edge of each blade to move slowly backward until the blade is by the rotation of the roll carried out of contact with the paper. In the meantime the paper is engaged by succeeding blades of the two rolls, and the action just described is repeated on each blade, so that, even if but one set of rolls were employed, every portion of the paper would in passing through the same be subjected to one or more such kneading or breaking and drawing actions and would be thereby reduced to a relatively soft and pliable condition. I prefer, however, to employ, several sets of rolls, for example four, as shown. The first rolls intermesh with each other to a comparatively slight depth, and their effect on the paper is correspondingly less than would be the case if they intermeshed to a greater extent. The rolls of the remaining sets intermesh to successively greater depths, with correspondingly greater effects on the paper, and the latter is thus brought gradually to the desired degree of softness and pliability. The use of more than one set of rolls also insures that every portion of the paper is acted on several times, so that one passage of the paper through the rolls will bring it to the desired condition; whereas with a single set, a very stiff paper might have to be passed several times through the same.

Since the degree of softness and pliability imparted to the paper depends on the amount of working or kneading to which it is subjected, it is clear that the final condition of the paper can be varied practically as desired by varying the extent to which the kneading rolls intermesh. Substantially equivalent results can be obtained in a machine in which several sets of rolls are used, as in the drawings, by removing the last set, or the last two sets, etc., thereby reducing by so much the total working or kneading action.

It is clear that in any case the tension required to draw the paper through the rolls should be well within the tensile strength of the paper, to avoid rupture of the same. Consequently the rolls must not inter-

mesh to such an extent that the friction of the paper on the bars or blades would necessitate the use of greater force than the paper can withstand. In the machine illustrated, the paper is drawn through the rolls by rotating the winding drum at a higher peripheral speed than that of the rolls; the speed of the former being of course not so great as to produce a tension greater than the paper can stand. But as the diameter of the roll on the drum increases the speed of travel of the paper and the tension thereon of course also increase. Hence it is essential that either the speed of drum be decreased or that of the kneading rolls increased, so that the friction of the paper on the roll blades will be approximately constant. The latter method is in some respects preferable, the mechanism therefor being quite simple, and I therefore employ the same in the machine illustrated. For this purpose I suspend a friction roller *G* at the lower ends of hangers *g*, *g'*, pivoted at their upper ends to a transverse shaft *G'*. The roller is arranged to bear firmly against the roll of paper on the winding drum, so as to be rotated by frictional contact with the paper, and carries at one end a pulley *g*², connected by a belt *g*³ with a pulley *g*⁴ on the shaft *G'*. On the same shaft, alongside of the last mentioned pulley is another pulley *g*⁵, connected by a belt *g*⁶ with a pulley on a second shaft, *G*². The latter shaft also has a pulley *g*⁷, connected by a belt *g*⁸ with the pulley on the adjacent end of the driving shaft. It is clear that in this construction the speed of the driving shaft, and the kneading rolls, depends upon the peripheral speed of the roll of paper on the winding drum, and that as the speed of the paper increases, on account of the increasing diameter of the winding roll, the roller *G* will rotate correspondingly faster and with it the driving shaft and the kneading rolls. Consequently, while the paper may pass at a higher speed through the machine, the tension on the paper remains about the same and likewise its slip over the kneading blades. Keeping the slip substantially constant is advantageous in at least one other particular also, in that the effect on the paper is thereby made practically uniform, which would not be the case if the slip were materially altered.

Any tendency of the paper to wrinkle or fold longitudinally after leaving the supply roll may be counteracted by suitable spreaders *H*, located at the rear of the several sets of kneading rolls, as shown in Fig. 1. The spreaders are higher at their centers than at their ends, as will be seen in Fig. 5, with the result that the paper in passing over the spreaders is subjected to a slight transverse tension, which effectually prevents the formation of longitudinal wrinkles or folds.

As is well known, some papers, particularly the heavier kinds, are formed by uniting two or more layers or films of pulp in the wet state. Thus united the several layers form a single, firm sheet of paper. The action of the kneading rolls on such paper is not only to render the paper soft and pliable in the manner described, but also to loosen the layers from each other at numerous points, leaving them adhering at intermediate points. This result can readily be observed by bending the paper, causing the separated portions of the layer on the inside of the bend to bulge out and form blister-like protuberances. I have devised

80

90

means whereby this effect, that is, the loosening of the layers composing the sheet, can be utilized to good advantage for the manufacture of imitation leather. For this purpose I provide, at the end of the machine 5 adjacent to the winding drum, a number of transverse bars, J, J', J'', J³, two or more of which are located in different horizontal planes. The paper issuing from the last set of rolls passes under the first bar, J, upward over the second, J', down and under the third, 10 J'', and over the fourth, J³, to the winding drum. The effect of these bars, which are of comparatively small diameters, and of course smooth enough to allow the paper to move over them without undue friction, is to produce the blisters mentioned above and then 15 fold down the bulged portions of the layer, forming slight ribs or ridges across the sheet. Thus when the paper reaches the first bar, the upper layer will bulge inwardly, that is, upwardly, wherever it is loosened from the lower layer. But in passing under the bar 20 the pressure thus produced on the blistered folds that part of the layer backward and presses it firmly down on the other layer. At the next bar the lower layer becomes the innermost, and the blisters formed therein are folded backward as in the first layer and formed into ribs or 25 ridges. This blistering and folding action is again produced on both sides of the paper by the third and fourth bars, on loosened portions of the layers that may not have been affected by the first bars, or on portions which may have been loosened by the first bars. In 30 this way each side of the sheet is marked with ribs or ridges extending in a direction substantially parallel with the bars which produce them, of varying lengths and varying distances apart. With bars arranged parallel to each other the effect is very much like 35 so-called "straight grained" morocco; but if the bars are arranged at angles to each other, for example 45°, the ribs produced by one bar will cross those produced by the bar or bars which are set at an angle thereto, and the result will be a very fair imitation 40 of alligator skin. The various ribbed effects are much desired in imitation leather, and heretofore it has been necessary to produce the ribs by embossing, which is liable to tear or cut the paper or at least weaken it at the ridges or ribs so formed. The means 45 which I employ for producing the ribbed or grained effect has no tendency to tear or cut the paper and does not weaken it to any degree that I am able to detect. The ribbing process appears to shorten the paper somewhat and also make it slightly heavier or 50 thicker. The effect of the ribbing bars of course does not depend upon any particular kind of devices for separating the layers of the paper.

In general, paper treated by my invention will be found to be singularly soft and pliable, with the stiffness and slight springiness or resiliency, due to the 55 sizing, entirely eradicated; although the strength of the paper, which is due in large measure to the sizing, is not materially impaired, if at all. All kinds of paper, issuing from the kneading devices, will be 60 found to have perfectly smooth surfaces, even the multilayer paper referred to above, the ribbed effect being produced in the latter by the ribbing bars above described.

It will be clear to those skilled in the art that the 65 invention can be embodied in a variety of ways.

For example, it will be apparent from Fig. 2 that substantially the same results would be produced if the rolls were stationary, as would be the case if the belt 70 g⁸ were thrown off the pulley on the driving shaft. In fact several spaced blades might be arranged in two straight rows, one above the other, with the blades of one row projecting into the spaces between the blades in the other row. The chief advantage of revolving blades over stationary blades for the purpose resides in the fact that the former type of machine 75 has a much greater output, for the reason that with stationary blades the actual speed of the paper is the same as its movement relative to the blades, and hence must be comparatively low to avoid tearing, or straining the paper unduly; whereas with revolving 80 blades the actual speed of the paper may be much greater than the slip since the blades are themselves advancing.

Other modifications might be mentioned, but those referred to are sufficient to make it clear that the invention is not confined to the particular machine herein specifically described.

What I claim is:

1. In a machine for softening paper, the combination of kneading rolls, between which the paper passes, and 90 means for drawing the paper between the rolls to cause slip of the paper relative to the portions of the rolls engaging the same, as set forth.

2. In a machine for softening paper, the combination of kneading rolls having intermeshing blades, and means for 95 drawing the paper between the rolls to produce a positive slip over the edges of the blades thereon, as set forth.

3. In a machine for softening paper, the combination of kneading rolls, between which the paper passes, means for rotating the rolls, and means for causing the paper to 100 travel between the rolls at a higher speed than the peripheral speed of the rolls, as set forth.

4. In a machine for softening paper, the combination of kneading rolls, between which the paper is passed, means for rotating the rolls, and a winding drum rotating at a 105 higher peripheral speed than the rolls, to receive the paper therefrom, as set forth.

5. In a machine for softening paper, the combination of kneading rolls, between which the paper is passed, and a winding drum to receive the paper from the rolls, operating 110 at a speed sufficient to draw the paper between the rolls and produce a positive slip of the paper relative to the portions of the paper engaging the same as set forth.

6. In a machine for softening paper, the combination of kneading rolls having intermeshing blades adapted to 115 produce successive folds in the paper passing between them, and means for producing movement of the paper relative to the blades, as set forth.

7. In a machine for softening paper, the combination of rolls for kneading the paper and feeding it forward, and 120 means for causing the paper to travel at higher speed than the feed of the rolls, as set forth.

8. In a machine for softening paper, the combination of a plurality of sets of kneading rolls, through which the paper passes, and means for causing the paper to travel at 125 a higher speed than the peripheral speed of the rolls, as set forth.

9. In a machine for kneading paper, the combination of a plurality of bladed rolls arranged in sets intermeshing at successively greater depths, and means for rotating the 130 rolls, as set forth.

10. In a machine for softening paper, the combination of a plurality of bladed rolls arranged in sets intermeshing at successively greater depths, between which rolls the paper passes, means for rotating the rolls, and means for producing movement of the paper relative to the blades of the rolls, as set forth.

11. In a machine for softening paper, the combination of kneading rolls between which the paper passes, means

- for causing the paper to travel at a higher speed than the peripheral speed of the rolls, and means for exerting tension on the paper transverse to its line of travel, as set forth.
- 5 12. In a machine for softening paper, the combination of kneading rolls between which the paper passes, means for causing the paper to travel at a higher speed than the peripheral speed of the rolls, and a transverse spreader engaging the paper to exert tension on the paper trans-
10 verse to its line of travel, as set forth.
13. In a machine for softening paper, the combination of a plurality of sets of kneading rolls between which the paper passes, means for causing the paper to travel at a higher speed than the peripheral speed of the rolls, and
15 one or more transverse spreaders engaging the paper to exert tension on the paper transverse to its line of travel, as set forth.
14. In a machine for softening paper, the combination of kneading rolls, between which the paper passes, a winding drum to receive the paper from the rolls, and means for rotating the rolls and drum with a constant difference of speed, as set forth.
- 20 15. In a machine for softening paper, the combination of kneading rolls, between which the paper passes, a winding drum to take up the paper from the rolls, and 25 means for rotating the said rolls at a uniform speed relative to the take-up of the paper by the winding drum, as set forth.
16. In a machine for softening paper, the combination of kneading rolls, between which the paper passes, a 30 winding drum to take up the paper from the rolls, a friction roller bearing on the paper on the drum, and means for driving the said kneading rolls from said friction roller, as set forth.
17. The combination of means for loosening or separating portions of the layers of multilayer paper, and means for producing folds in loosened or separated portions of the said layers, as set forth.
18. The combination of means for loosening or separating portions of the layers of multilayer paper, and a 35 plurality of bars engaging the paper and producing folds in loosened or separated portions of the said layers, as set forth.
